UNITED STATES PATENT OFFICE

109,744

DESIGN FOR A CABINET FOR AN ACTUATOR GOVERNOR

Helmer Walter Thorell, Rockford, Ill., assignor to
Woodward Governor Company, Rockford, Ill.,
a corporation of Illinois

Application September 20, 1937, Serial No. 71,694

Term of patent 14 years

To all whom it may concern:

Be it known that I, Helmer Walter Thorell, a citizen of the United States, residing at Rockford, in the county of Winnebago and State of Illinois, have invented a new, original, and ornamental Design for a Cabinet for an Actuator Governor, of which the following is a specification, reference being had to the accompanying drawing forming part thereof.

In the drawing:

Fig. 1 is a perspective view of the actuator governor cabinet showing my design;

Fig. 2 is a similar perspective taken from the rear;

Fig. 3 is a top plan view, and

Fig. 4 is an enlarged perspective detail of a top corner.

The dominant features of the design are shown in full lines.

I claim:

The ornamental design for a cabinet for an actuator governor, substantially as shown and described.

HELMER WALTER THORELL.
